BOTTLE CAPPING MACHINE

Geoffrey Ewart Ford, Bow, London, England, assignor to Fords (Finsbury) Limited, London, England, a British company

Application October 22, 1949, Serial No. 122,968
In Great Britain June 12, 1948

11 Claims. (Cl. 226—85)

1

The present invention relates to a machine for capping bottles, such as milk bottles, and more particularly to machines of the type which punch caps from a sheet of metal foil, such as aluminium foil, which is fed through the machine, applies a punched cap to the mouth of the bottle, and finally crimps the cap on to the bottle by pressing the edge of the cap into a groove around the outside of the bottle mouth.

The present invention has for its object to provide a machine of this type which is of simple construction and which is particularly suitable for hand operation, in which the operation of the different parts of the machine is so timed that simultaneously with the crimping of a cap on one bottle a further cap is punched from the metal strip and delivered to the station where it is to be applied to the mouth of another bottle. A further object of the invention is to provide a bottle capping machine of the type referred to having improved means for feeding the metal strip through the machine whereby the foil may, if desired, be fed through the machine without actuating the punch, whereby the initial loading of the machine is facilitated. A still further object of the invention is to provide an improved device for applying the punched caps to the mouth of the bottle. Another object of the invention is to provide an improved cap-closing device for closing caps of thin sheet metal or other suitable material into the groove around the mouth of the bottle.

The invention consists in a bottle capping machine comprising a punch and die for blanking and forming a cap from a strip of metal foil which is fed through the machine upon the reverse or opening movement of the die, wherein the mechanism is operated by a reciprocating shaft, which is preferably operated by a hand lever, which is coupled to the strip advancing drive wheel through a latching device which moves freely with respect to the wheel during the forward movement of the shaft and latches with an abutment thereon before the dies are closed, the latch driving the abutment and the wheel during the return movement of the shaft, whereby the foil can be fed through the machine without closing the dies.

Preferably the wheel is coupled to two pairs of feed rollers for the foil which are arranged on opposite sides of the die, the pair of feed rollers on the outlet side of the die being driven at a faster rate than the pair of feed rollers on the inlet side whereby the foil is maintained tensioned between the dies.

The invention also consists in the means for

2

applying a formed cap to a bottle. According to this feature the formed caps are fed, for example by gravity, to a holder in which the caps are positioned standing edgewise in a substantially vertical position. Upon a bottle being passed through the machine beneath the holder, the neck of the bottle engages with the skirt of the cap thereby forcing the cap forwardly against a spring-pressed or gravity operated member or plate which hinges upwardly and causes the cap to fit over the mouth of the bottle, the plate urging the cap on to the mouth of the bottle as the bottle is fed therewith.

A further feature of the invention consists in the cap-closing device for closing caps of thin sheet metal or other suitable material on to the bottle or like container by pressing the skirt of the cap into a groove around the outside of the mouth of the bottle. The invention therefore also consists in a cap-closing device of the type comprising a relatively thick disc or ring of rubber or like flexible material having a recess in its undersurface which is adapted to fit over a cap fitted to the mouth of a bottle, the pressing of the closing device against the cap causing the closing edge of the rubber surrounding the recess to close inwardly and press the skirt of the cap into the groove in the bottle, wherein there is also provided a movable pressure plate or member which is adapted to engage with the back of the rubber closing disc or ring and serves for urging the centre of the latter downwardly in order to expand the closing edge of the recess in the rubber disc or ring and thus facilitating the fitting of the recess over the cap positioned on the mouth of the bottle. Upon pressing the closing device on to the bottle, the pressure plate moves rearwardly with the rubber disc or ring and allows the closing edge to press the skirt of the cap into the groove around the mouth of the bottle.

Preferably the pressure plate is spring-pressed downwardly so that the closing disc or ring is normally urged to its outer and open position, pressure of the closing device upon the bottle also moving the pressure plate upwards against the action of the spring.

The pressure plate conveniently comprises a circular plate carried at the end of a rod which is slideable in the handle of the closing device or the stem by which it is attached to the movable member of a bottle capping machine, the spring being fitted between the upper surface of the pressure plate and the material of the handle or stem surrounding the aperture in which the rod moves.

In order that the invention may be more clear-

ly understood, an embodiment thereof will now be described, by way of example, with reference to the accompanying drawings, in which:

Fig. 1 shows a perspective view of a bottle capping machine according to the invention;

Fig. 2 shows a side view of the machine looking from the side opposite to that of Fig. 1;

Fig. 3 shows a sectional plan view along the line A—A in Fig. 2;

Fig. 4 shows a vertical section along the line B—B in Fig. 3 with the cap-closing device in position to receive a bottle;

Fig. 5 is a scrap section of the closing device shown in Fig. 4 but with the closing device advanced towards the cap upon a bottle;

Fig. 6 is a view similar to Fig. 5 but with the closing head fully advanced to the position in which it crimps the cap upon the bottle;

Fig. 7 is a scrap section along the line C—C in Fig. 3;

Fig. 8 is a sectional plan through the cap applying device along the line D—D in Fig. 2.

Referring to the drawings, the operating mechanism of the machine is carried by a pillar 1 mounted on a base 2 provided with a groove or guide-way 3 for guiding the bottles 4 to be capped during their passage beneath the cap-applying device generally indicated by 5, and the cap closing device generally indicated by 6. The mechanism is carried by a box-like frame 7, between opposite side walls 7a, 7b of which extends an operating shaft 8 carrying an operating hand lever 9, a spring 10 being provided for urging the lever 9 to its normal resting position in which it is substantially upright. Secured on the shaft 8 is a boss 11 carrying an arm 12 which is pivotally connected by a bolt 13 to a forked link 14, the other end of which is pivotally connected to a platen 15 carrying the die 16. The platen carries bushes 17 slideable on guide bars 18 carried from the front wall 7c of the box-frame so that, when the shaft 8 is rotated in an anti-clockwise direction (as viewed in Fig. 4) by pulling down the lever 9, the toggle action of the member 12 and 14 moves the die 16 towards the punch 19 which is carried by the front wall 7c.

Projecting through a bushing 20 secured in the bottom of an hollow part 7e projecting from the bottom wall 7d of the box-like frame and so that it is guided to move in a vertical direction, is the cap-closing device 6. This cap-closing device comprises a pair of annular clamping members 21, 22 forming a holder for the rubber closing ring 23 which is moulded with the cross-section shown in Figure 4 with an annular recess 24 on its lower face which is adapted to fit over the capped mouth of a bottle. The two clamping members 21, 22 are screw-threaded together, the peripheral edge of the rubber closing ring 23 being clamped therebetween when the members 21 and 22 are screwed together. The upper member 22 is hollowed to allow clearance for the movement of the closing ring 23. The stem 25, which is slideable in the bush 20, is secured to the upper surface of the member 22 and extends coaxially therewith. The cap-closing device 6 is urged to its uppermost position by means of the spring 26 bearing against a disc 27 secured by screws 28 to the upper end of the stem 25. The stem 25 is provided with a hollow passage 29 extending from its upper end into which is fitted a member 30 carrying a roller 31 which is arranged in alignment with and adapted to be engaged by the cam 32 carried by the bush 11. The position of the roller 31 may be ad-

justed by the stud 34 screwed into the bottom surface of the member 30 and adapted to bear against the end of the passage 29. Rotation of the member 30 within the passage 29 may be prevented by making these two parts of irregular cross-section, or in any other convenient manner.

The cap-closing device is also provided with a pressure plate 35 which is conveniently of circular form and slightly larger in diameter than the aperture 36 in the centre of the closing ring 23 but of a smaller diameter than the closing recess 24 on the undersurface of the ring 23. Secured to and extended upwardly from the back of the pressure plate 35 is a rod 37 slideable in a hole 38 formed in the stem 25 and connecting with the passage 29, the upper end of the rod 37 being provided with a head 39 or other means for preventing it from passing through the hole 38. Surrounding the rod 37 between the pressure plate 35 and the stem 25 is a spring 40 which normally urges the pressure plate into the position shown in Fig. 4 with the closing ring 23 pressed downwardly so that the side walls of the closing recess 24 are inclined outwardly and thereby enlarged to receive the top of a bottle with the metal cap positioned thereon. The lower end of the stud 34 is recessed to permit vertical movement of the head 39 therein. The operation of the cap-closing device 6 will be described later.

The coil of aluminium foil 41 from which the caps are made is carried on a roller 42 having reduced diameter portions 43 adapted to fit in bearing grooves 44 formed on an extension bracket 45 projecting from the back of the top cover 46 of the box-like frame 7. The aluminium foil 41 is fed beneath a guide roller 47 and between a pair of felt pads 48 which may be impregnated with oil for lubricating the foil for punching. It is then fed over another idler roller 49 to a pair of feed rollers 50, 51 which serve for feeding the foil into the machine. The roller 50 extends between and is rotatable in bearings carried in the side walls 7a, 7b of the frame, whilst the roller 51 is carried in bearings 52 supported by studs 53 slideable in bushes 54 carried by the front wall 7c. The ends of these studs 53 project outside the front wall 7c and are spring-pressed inwardly by the spring 54 bearing upon the centre of the lever 55 which bridges the ends of studs 53 outside the front wall 7c. In this way the roller 51 is spring-pressed towards the roller 50 to grip the foil 41 therebetween. The surfaces of one or both of the rollers 50, 51 may be roughened.

The two rollers 50, 51 are geared together by pinions 56, 57 carried by the rollers 50, 51 respectively at one end thereof. The roller 50 is also provided at its other end with a pinion 58 which is geared to a large diameter toothed wheel 59 mounted for rotation about a spindle 60 carried by the side wall 7b. This toothed wheel 59 is provided with a series of radial grooves 61 on its inner surface. Also freely mounted on the spindle 60 is an arm 62 having a latch 63 pivoted about a bolt 64 screwed into the end of the arm 62 and urged by a leaf spring 65 towards the wheel 59 so that the latch 63 is adapted to engage with the radial grooves 61 on the inner surface of the wheel 59. The arm 62 carrying the latch is coupled through a lever 66 to a second lever 67 (Figs. 4 and 7) which is freely rotatable about the operating shaft 8, this second lever being urged by a spring 68 to a forward position (as shown in Fig. 7) where the latch 63

engages one of the radial grooves 61. Co-operating with the lever 67 is a push member 69a which is carried by the member 69 fast with the shaft 8. The member 69a engages with the lever 67 and pushes it, and the arm 62 and latch 63 coupled thereto, backwards during the reverse or backward movement of the operating handle 9, thereby moving latch 63 and driving the wheel 59 locked thereto to rotate the feed rollers 50, 51 to feed the foil 41 by the correct distance for forming another cap. Upon forward movement of the operating handle 9 the push member 69a allows the lever 67 to move forwards under the action of the spring 68 so that the latch 63 is advanced to the position shown in Fig. 7 to engage with the next radial groove 61, in which position it stops, for example by lever 66 wedging against the bushing of the arm 62 as shown in Fig. 7. If the spring 68 should fail to move the lever 67, the latter is positively moved by the projection 69b on the member 69 when the handle 9 is pulled forwards. In this position the die 16 and punch 19 are not closed, but further forward movement of the operating handle 9 can be effected without moving the latch 63, this further forward movement completing closure of the die and punch to punch and form a closing cap from the foil. Reverse movement of the handle 9 opens the die and punch and the push member 69a moves the latch 63 and the wheel 59 to drive the feed rollers 50, 51 and advance the metal foil through the machine. Reverse movement of the handle 9 is limited by the arm 12 engaging against an adjustable stop 78.

Preferably a further pair of feed rollers 70, 71 are disposed beneath the die at the bottom of the frame 1, the roller 70 being provided with a pulley 72 connected by a belt 73 to a pulley 74 on the end of the roller 50 whereby the lower roller 70 is driven by the upper feed roller 50. Only one of the lower rollers, viz. the roller 70 is driven, the second roller 71 being removable from bearing slots 77 to facilitate threading the foil 41 between the two rollers 70, 71, and being held in position by the arm 75 urged by the spring 76 to bear on the surface of the roller 71 and to hold it close against the roller 70 to grip the foil therebetween. The rollers 70, 71 are preferably driven at a higher speed than the rollers 50, 51 in order to maintain the foil 41 taut between the two pairs of rollers for which purpose the pulley 74 may be made of larger diameter than the pulley 72.

The cap is formed by the die 16 and punch 19. The punch 19 comprises a central cylindrical member 100 having a removable face 101 which is embossed with the lettering which has to appear on the cap. The members 100 and 101 are secured against the base of a cup-shaped member 102, spanning an aperture 103 in the front wall 7c of the frame, by means of the threaded bolts 104, 105 respectively which project through the tubular boss 102a extending from the back of the member 102. The front edge of the member 102 carries a shear ring 106 adapted to co-operate with the outer peripheral edge of the annular member 107 of the die carried by the platen 15 to shear a disc from the foil from which the cap is formed. Within the annular gap defined by the internal periphery of the shear ring 106 and the forming member 100 is arranged an annular ejector ring 108 carried by pins 109 from the annular member 110 slidable axially on the external surface of the stem 102a against the action of a spring 111 which is held

between the rear surface of the member 110 and a collar 112 screwed on to the end of the stem 102a.

Surrounding the shear ring 107 of the die is the pressure plate 113 slidable longitudinally on the external surface of the ring 107 and on guide rods 114 against the action of the spring 115. This pressure plate 113 bears against the face of the shear ring 106 to hold the foil 41 firmly whilst the disc from which the cap is to be formed is sheared from the foil.

The disc after being sheared is held in position on the cylindrical forming member 100 by means of a pressure ring 116 slidable within the annular member 107 against the action of the spring 118. Fitted within the pressure ring 116 and carried from the platen 15 is a pressure pad 119 having a face 119 of rubber or like resilient material which when the die and punch are closed together presses the foil into the embossed lettering in the member 101 to mark the centre of the cap.

When the die 16 is advanced towards the punch 19, the pressure ring 116 first bears against the cylindrical member 100 to hold the foil thereagainst and then the pressure plate 113 bears against the surface of the shear ring 106 again to grip the foil around the disc to be sheared. The member 107 then shears the disc and on being further advanced forces back the ejector ring 108 and forms the cap over the external periphery of the member 100, the pressure pad 119 finally embossing the centre of the formed cap. Upon the reverse movement of the die, the ejector ring 108 forces the cap off the member 100. If the cap is retained in the ring 116 it is removed by the wire finger 120 which moves across the face of the die. The finger 120 is carried at the end of the wire arm 121 which is rotatable with the shaft 122 rotatable in the wall 7a and is urged by the spring 123 to turn the arm 121 to raise the finger 120 from between the die 16 and punch 19. The shaft 122 also carries an arm 124 which engages the arm 12 when the die is retracted to turn the shaft 122 against the action of the spring 123 and thereby move the finger 120 across the face of the die 16 and remove the formed cap adhering in the ring 116.

The walls 7a, 7b may be provided with transparent windows 125, 126 respectively through which the operation of the die and punch may be viewed.

The caps formed between the die 16 and punch 19 and ejected during the reverse movements of the operating shaft 8 fall into a guide channel 80 along which they roll to a holder 81 between the frame 1. This holder comprises a pair of side walls 82, 83 having a slot along its bottom of such a length that a segment of a cap 84 can project therebeneath. This slot is defined by a pair of pins 85. The wall 83 opposite to the side from which the bottles are fed is hinged at 86 and urged by a spring 87 into its upright position. Upon a bottle 4 being moved along the guide-way 3 in the base 2, however, the neck thereof engages with the cap 84 projecting below the holder 81 and forces the hinged side wall 83 to move. Due to the inclination of the side wall 83 during its opening, the cap 84 is similarly inclined and folded over and onto the mouth of the bottle, the spring or gravity pressure exerted by the side wall 83 firmly pushing the cap 84 onto the bottle.

The wall 82 may be removed by releasing the screws 88. The bottle is then pushed forward 75 to the position beneath the cap-closing device

6 so that the next forward movement of the operating handle crimps the cap on to the bottle and simultaneously punches another cap which runs along the channel guide 80 to the holder 81 and is ready for fitting on to the next succeeding bottle.

The operation of closing a metal cap upon the neck of the bottle will be clearly understood from Figs. 4, 5 and 6. After a metal cap has been formed and applied to the neck of the bottle, as above described, the bottle is positioned beneath the cap-closing device 6 whereupon actuation of the lever 9 to form another cap causes the cap-closing device 6 to be pressed upon the top of the bottle, with the cap positioned thereon, to crimp the cap to the bottle by pressing the skirt of the cap into the groove 4a around the bottle neck. Fig. 5 shows the cap-closing device in an intermediate position with the cap entering the closing recess 24. The lower clamping member 21 is formed with its central aperture upwardly tapered as shown so as to guide the neck of the bottle into the closing device. This central aperture is preferably only slightly greater in diameter than the diameter of the cap 84 so that the cap is guided into the closing recess 24 of the closing ring 23, the closing edge of the recess 24 being opened out to a diameter equal to, and preferably greater than, the central aperture of the member 21 by reason of the pressure plate 35 bulging the closing ring downwardly as shown. In this position the closing edge of the recess 24 may bear against the inner surface of the lower member 21. Thus the bottle mouth and cap positioned thereon will always be guided into the closing recess 24.

Upon further downward movement of the cap-closing device 6, the central portion of the closing ring 23 and the pressure plate 35 are held stationary by bearing upon the top of the cap, whilst the external periphery of the closing ring 23 continues its downward movement with the members 21 and 22. During this further movement the spring 40 is compressed and, as shown in Fig. 6, the closing edge of the recess 24 closes inwardly and presses or crimps the skirt of the cap 84 into the groove 4a around the mouth of the bottle.

Upon the return movement of the lever 9, the cap-closing device 6 is raised by the spring 26, and the pressure plate 35 and closing ring 23 again assume the positions shown in Fig. 4. The bottle can then be slid along the guide 3 from beneath the cap-closing device 6 and the next bottle, which has received a cap as above described, is positioned beneath the cap-closing device.

The groove or guideway 3 in the base 2 may be of angular form, the angle being positioned directly below the cap-closing device 6 and locating the bottles in the cap-closing position.

For capping shorter bottles than that for which the machine is primarily designed, a platform may be provided which fits into the groove track in the base and is of such height that the shorter bottles, when placed upon it, will have their mouths at the correct level for picking up a cap and for sealing the cap thereon. In an alternative embodiment the frame only may be adjustable vertically on the pillar 1 to operate with different sizes of bottles.

For ease of use, the entry and exit ends of the groove 3 in the base 2 or the removable platform may have inclined portions 3a so that the bottles

may be slid smoothly from the bench into the groove.

The top of the machine may be provided with a cover 89 for hinging movement about a pivot 90 on the bracket 45 so that the cover 89 may be raised to insert a new roll of foil 41 into the machine. The bracket 45 may also carry a bottom casing member 91 for enclosing the coil of foil.

Whilst a particular embodiment has been described, it will be understood that various modifications may be made without departing from the scope of the invention. For example, instead of being hand-operated the machine may be adapted for power operation, by connecting the shaft 8 to be driven from an electric or other motor through a crank or other suitable mechanism to impart the back and forth motion to the shaft.

I claim:

1. A cap-closing device of the type referred to, comprising a relatively thick disc of rubber-like flexible material having a recess in its under surface, a holder supporting the periphery of said disc, means for clamping the periphery of said disc to the holder, a movable pressure plate which is smaller than the diameter of the recess, means for supporting the movable pressure plate in axial alignment with the recess in the disc, and means for moving the movable pressure plate relative to said holder to engage with the upper surface of the disc and so urge the centre of the latter downwardly in order to expand the closing edge of the recess of the disc and thus facilitate the fitting of the recess over a cap positioned on the mouth of a bottle.

2. Device as claimed in claim 1 wherein the pressure plate comprises a disc carried at the end of a rod which is slidable in a stem attached to the holder.

3. Device as claimed in claim 2, comprising a spring acting on the back of the pressure plate so that the latter is spring-pressed downwardly and the recess in the closing disc is normally urged to its open position.

4. Device as claimed in claim 3, comprising two annular members, means for crimping the periphery of the closing disc between two said annular members and a central aperture formed in one of said annular members in alignment with the recess in the closing ring or disc.

5. A bottle capping machine comprising means for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, a spring for advancing the latching device during forward movement of the shaft, a stop for limiting forward movement of the latch by the spring beyond the position in which it is latched with the abutment, further forward movement of the shaft to close the punch and die then taking place without further forward movement of the latch and said latch driving the abutment and wheel during the return movement of the shaft.

6. A bottle capping machine comprising means

for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, the latch driving the abutment and wheel during the return movement of the shaft, a holder to which the formed caps are fed and in which said caps are positioned standing edgewise in a substantially vertical position, means for passing a bottle beneath the holder causing the neck thereof to engage with the skirt of a cap and thereby force the cap forwardly against a member which hinges upwardly and causes the cap to fit over the mouth of the bottle, said member urging the cap on to the mouth of the bottle as the latter is fed therepast.

7. A bottle capping machine comprising means for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, a spring for advancing the latching device during forward movement of the shaft, a stop for limiting forward movement of the latch by the spring beyond the position in which it is latched with the abutment, further forward movement of the shaft to close the punch and die then taking place without further forward movement of the latch, said latch driving the abutment and wheel during the return movement of the shaft, a holder to which the formed caps are fed and in which said caps are positioned standing edgewise in a substantially vertical position, means for passing a bottle beneath the holder causing the neck thereof to engage with the skirt of a cap and thereby force the cap forwardly against a member which hinges upwardly and causes the cap to fit over the mouth of the bottle, said member urging the cap on to the mouth of the bottle as the latter is fed therepast.

8. A bottle capping machine comprising means for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, a spring for advancing the latching device during forward movement of the shaft, a stop for limiting forward movement of the latch by the spring be-

yond the position in which it is latched with the abutment, further forward movement of the shaft to close the punch and die then taking place without further forward movement of the latch, said latch driving the abutment and wheel during the return movement of the shaft, two pairs of feed rollers for the foil arranged on opposite sides of the die and punch and coupled to the driving wheel, and means for driving the pair of feed rollers on the outlet side at a faster rate than the feed rollers on the inlet side, whereby the foil is maintained tensioned as it passes between the punch and die.

9. Machine as claimed in claim 8, wherein the driving wheel is provided with a plurality of radial grooves on one of its side faces to form the abutments into which the latch is adapted to engage.

10. A bottle capping machine comprising means for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, the latch driving the abutment and wheel during the return movement of the shaft, two pairs of feed rollers for the foil arranged on opposite sides of the die and punch and coupled to the driving wheel, means for driving the pair of feed rollers on the outlet side at a faster rate than the feed rollers on the inlet side, whereby the foil is maintained tensioned as it passes between the punch and die, a holder to which the formed caps are fed and in which said caps are positioned standing edgewise in a substantially vertical position, means for passing a bottle beneath the holder causing the neck thereof to engage with the skirt of a cap and thereby force the cap forwardly against a member which hinges upwardly and causes the cap to fit over the mouth of the bottle, said member urging the cap on to the mouth of the bottle as the latter is fed therepast.

11. A bottle capping machine comprising means for guiding a strip of metal foil between a punch and a die, means for closing the punch and die together for blanking and forming a cap from the strip of metal foil, means for opening the punch and die, means for feeding the metal foil through the machine during the opening movement of the punch and die, a reciprocating shaft for actuating the die opening and closing means, a driving wheel for advancing the metal strip, a latching device coupled to said shaft which moves freely with respect to the wheel during the forward movement of the shaft and latches with an abutment before the punch and die are closed, a spring for advancing the latching device during forward movement of the shaft, a stop for limiting forward movement of the latch by the spring beyond the position in which it is latched with the abutment, further forward movement of the shaft to close the punch and die then taking place without further forward movement of the latch, said latch driving the abutment and wheel during the return movement of the shaft, two pairs of feed rollers for the foil arranged on opposite sides of

11

the die and punch and coupled to the driving wheel, means for driving the pair of feed rollers on the outlet side at a faster rate than the feed rollers on the inlet side, whereby the foil is maintained tensioned as it passes between the punch and die, a holder to which the formed caps are fed and in which said caps are positioned standing edgewise in a substantially vertical position, means for passing a bottle beneath the holder causing the neck thereof to engage with the skirt of a cap and thereby force the cap forwardly against a member which hinges upwardly and causes the cap to fit over the mouth of the bottle, said member urging the cap on to the mouth of the bottle as the latter is fed therewith. 15

GEOFFREY EWART FORD.
